HEAT CONDUCTING SKEWER OR THE LIKE

Paul K. Dawson, Los Angeles, Calif.

Application March 31, 1958, Serial No. 50,259

Term of patent 14 years

(Cl. D44—29)

Figure 1 is a top plan view of the heat conducting skewer;

Figs. 2 and 3 are respective side elevations of the skewer;

Figs. 4 and 5 are end views, taken in the direction of the arrows 4 and 5 of Fig. 3; and

Fig. 6 is an enlarged sectional view, taken along a plane indicated by line 6-6 of Fig. 3.

I claim:

The ornamental design for a heat conducting skewer or the like, substantially as shown.
